[57] CLAIM

The ornamental design for a wood burning stove, substantially as shown and described.

DESCRIPTION

FIG. 1 is a front view of a wood burning stove showing my new design;

FIG. 2 is a top plan view thereof;

FIG. 3 is a rear elevational view thereof;

FIG. 4 is a bottom view thereof; and

FIG. 5 is an elevational view of the right side thereof. The left side thereof is substantially a mirror image of FIG. 5.

FIG.1

FIG.2

FIG. 3

FIG. 4

FIG. 5
